HANDLE FOR SPRAY APPARATUS

Clarence A. Price, Ann Arbor, and Edward Fischer,
Adrian, Mich., assignors to Bradson Manufacturing
Corporation, Saline, Mich., a corporation of Michigan

Application December 10, 1956, Serial No. 44,128

Term of patent 14 years

(Cl. D62—2)

Figure 1 is a perspective view of a handle showing our new design;

Fig. 2 is a top plan view of the handle; and

Figs. 3, 4 and 5 are front, side and rear elevations thereof, respectively.

The dominant feature of our design resides in the element shown in full lines in the drawing.

We claim:

The ornamental design for a handle for spray apparatus, as shown and described.
